GUSTAV BOMMER, OF BROOKLYN, NEW YORK, ASSIGNOR TO EMIL BOMMER, OF BROOKLYN, NEW YORK

HINGE CONSTRUCTION

Application filed June 11, 1931. Serial No. 543,579.

This invention relates to an improved construction for door hinges, its object being to provide a very simple and desirable method and structure by which directly and in a rigid and unyielding manner to secure the axial pivot shaft of the hinge to the supporting bracket which is attached to the door frame.

In hinges of the type in which the hinge 10 casing, which contains the torsional acting spring, turns upon the pivot shaft and with the bracket attached to the door, great difficulty is experienced in obtaining such a secure connection between the pivot shaft and 15 the supporting bracket on the door jamb that the pivot shaft will not in time, under the turning of the door and hinge casing, work loose and yield in a circular direction, with the result, amongst other undesirable features 20 which follow from such relative yielding, that the door gets out of alignment with the door jamb.

The purpose and object of the present invention are to provide a simple and practical 25 construction by means of which, when the pivot shaft and its support are once secured directly together, they will remain secured together in a rigid, unyielding condition, although the parts can be separated if an occasion 30 should arise requiring their separation.

The features of the invention will be more fully described hereinafter and finally 35 claimed. One simple and practical example of the invention, as reduced to practice, is shown in the accompanying drawing, in which:—

Figure 1 is an elevation and partial section of my improved spring hinge embodying 40 the features of the invention forming the basis of this present application;

Fig. 2 represents a fragmentary sectional view on a larger scale, taken on the line 2—2 of Fig. 1;

Fig. 3 is an elevational view, showing the parts separated but in proper aligned order for assembly;

Fig. 4 is an enlarged fragmentary sectional detail, illustrating the relation which 50 an axially extending tooth on the pivot shaft

bears to the socket wall to be penetrated thereby; and

Fig. 5 is a fragmentary section on an enlarged scale, showing the axial teeth as they appear when wedged into the wall of the 55 socket.

Referring now to the parts shown in the accompanying drawing, 10 denotes an angular bracket for attachment to a door frame or jamb and the vertical portion of this 60 bracket is provided with the usual apertures 11 adapted to receive screws or the like whereby to be secured to the frame or jamb. 12 designates a horizontal bracket for attachment to the lower edge of the door and 65 this bracket is provided with apertures 13 for receiving the attaching screws or the like. Fixed to one end of the bracket 12 is a cylindrical casing 14 in which is centrally positioned a cylindrical pivot shaft 15, the 70 upper end of the shaft being applied to a seat or bearing portion 16 provided for the purpose in the top of the casing and the lower portion of the shaft fitting in an opening or bearing provided by an annular flange 75 17 depending from the detachable bottom plate 18 of the casing. Disposed on the shaft within the casing are suitable upper and lower plates 19 and 20, suitably holed for the passage of the shaft; and encircling 80 the shaft between these two plates is a helical spring 21 the opposite ends of which are attached to the respective upper and lower plates. These plates are provided in well-known manner with projecting shoulders 22 85 which engage with suitable ribs or lugs 23 provided on the inside of the casing.

The cylindrical pivot shaft, in order to provide for its securement to the horizontal portion or body 24 of the bracket 10, extends 90 a considerable distance below the lower edge of the annular bearing flange 17. Its special construction includes a reduced intermediate portion 25 which is separated by an annular shoulder 26 from a larger portion 27 95 that constitutes as to its diameter a uniform continuation of the main cylindrical shaft, it being noted in this regard that the portion 27 extends a distance below the lower edge of the collar or bearing 17 before the 100

annular shoulder 26 is reached. The lower end of this shaft, following the reduced portion 25, comprises a further portion 28 which is exteriorly screw-threaded.

The horizontal or body portion 24 of the bracket 10 is provided with a circular opening or bore 29 of a diameter adapted snugly to receive the intermediate portion 25; and in the upper portion of the body 24 there is provided a circularly expanded seat 30 in open communication with the bore and concentric therewith. This seat 30 is of a diameter in some degree less than the diameter of the shaft portion 27. These parts are so proportioned and arranged that when the shaft is inserted with its intermediate part 25 engaging the wall of the bore 29, the screw-threaded end 28 will protrude well below the underneath face of the body 24, for the reception of a securing nut 31.

According to an important feature of the present invention, the circumference of the portion 27 below the flange 17 and contiguous with the annular collar 26 is cut all around to provide cutting teeth 32 which extend parallel with the axis of the pivot shaft; and by preference the annular corner between the shoulder 26 and circumference of the portion 27 is so made that the teeth, when cut, will extend somewhat below the plane of said annular shoulder 26, as best shown in Fig. 2. Under this arrangement, when the pivot shaft is inserted in the bore and forcibly moved axially downwardly therein the cutting teeth 32 cut into, and form their own seats 33 in, the body of the horizontal portion 24 surrounding the seat 30. To better enable the cutting operation and the formation of the seats 33 by the cutting teeth 32, the latter are hardened, preferably by the well-known cyanide hardening process. By turning the applied nut 31 tightly against the under face of the body 24, the pivot shaft will be drawn axially downwardly, the teeth 32 cutting for themselves the seats 33 as they are drawn downwardly through the material of the body 24. The pivot shaft may thus be drawn axially downwardly until the cutting teeth 32 are drawn into the material of the body for the distance necessary to make a rigid and unyielding connection directly between the pivot shaft and the material of the body. As the cutting teeth 32 cut the seats 33 the material portions 34 integral with the body 24 and which come between the teeth 32 as shown in Fig. 5, are wedged firmly between the teeth and interlock therewith so as to positively prevent any circular yielding of the cylindrical pivot shaft with respect to the supporting bracket.

In hanging the door, the cylindrical pivot shaft is inserted in the bore of the supporting bracket and the cutting teeth 32 are initially interlocked with the material thereof

in that position in which the door fastened, or to be fastened, to the bracket 12 will be in proper alignment with the door jamb. With the described construction, when the cutting teeth of the pivot shaft have been wedged and interlocked with the supporting bracket, a connection is established which does not work loose in time owing to the swinging of the door upon the pivot shaft; the nut 31 upon the threaded portion 28 and which is turned tightly against the underface of the body 24, naturally prevents the shaft from working axially upwardly for any release of the cutting teeth from their seats in the material of the body. It is in place to note here that the firm and unyielding connection which is provided by my present invention entirely eliminates the use of washers and similar means which are commonly used in the attempt to secure a rigid binding connection; and it will be further observed that in the present invention the cutting teeth provide a direct wedging and interlocking connection between the cylindrical pivot shaft and the body of the supporting bracket.

While by way of example, I have herein illustrated and described my improvements in connection with a pivot type hinge embodying a spring, it is to be understood that in practice my improvements may be employed with equal advantage and effect in connection with pivot hinges of types other than that herein shown whether embodying a spring or otherwise.

It is to be understood that in the practice of my invention, I reserve the right and privilege of resorting to all such legitimate changes and modifications in the form, construction, and relative arrangement of the various parts as may be fairly incorporated in the spirit and scope of the invention as claimed.

I claim:—

1. In a door hinge of the kind described, the combination of a fixture adapted to engage the door and formed with a cylindrical casing, a bracket for mounting the fixture on a door jamb, said bracket including a horizontal part having a vertical opening of cylindrical form extending therethrough, a vertical pivot shaft on which the casing is centrally mounted for turning movement, formed with a cylindrical portion extending below the bottom end of the casing and adapted to engage the opening, said cylindrical portion being of a length to extend downwardly through and well below the opening and having a screw-threaded region adjacent its lower end, cutting members projecting from the surface of the cylindrical portion at a locality above the screw-threaded region, extending parallel with the axis of the cylindrical portion and hardened, and a nut engageable with the screw-threaded end of the cylindrical portion, to be turned

against the horizontal part and adapted, on being turned thereagainst, to draw the vertical shaft downwardly through the opening and cause the hardened cutting members 5 to penetrate the material of the horizontal part, whereby securely to maintain the shaft locked to the bracket against turning movement despite the rotative force exerted upon the shaft by the turning of the casing there-
10 on.

2. In a door hinge of the kind described, the combination of a door fixture, a jamb bracket, means pivotally connecting the door fixture with the jamb bracket including a 15 hinge casing, a pivot shaft on which the casing is mounted for turning movement, extending downwardly therefrom and including in its construction a plain cylindrical portion separating an enlarged cylindrical portion above it from a screw-threaded region below it, a horizontal part provided on the bracket and having a cylindrical opening divided into smaller and larger diameters adapted respectively to receive the plain 20 and enlarged cylindrical portions of said shaft, with the screw-threaded region thereof protruding from said opening beyond the side of the horizontal part, cutting members projecting from the surface of the enlarged 25 portion of the shaft, extending parallel with the axis thereof and hardened, a nut engageable with said screw-threaded region, to be turned against the side of the horizontal part and adapted, when turned thereagainst, to 30 draw the shaft axially in the opening and cause the cutting members to penetrate the material of the horizontal part around the cylindrical opening of larger diameter and with the plain portion of the shaft guided 35 in the cylindrical opening of smaller diameter.
40

In testimony, that I claim the foregoing as my invention, I have signed my name hereto.
